UNITED STATES PATENT OFFICE.

ALLYN BOUGHTON, OF IOLA, KANSAS.

THRESHING-MACHINE COVER.

1,068,306.

Specification of Letters Patent. Patented July 22, 1913.

Application filed March 30, 1910. Serial No. 552,422.

To all whom it may concern:

Be it known that I, ALLYN BOUGHTON, a citizen of the United States, residing at Iola, in the county of Allen and State of Kansas, have invented certain new and useful Improvements in Threshing-Machine Covers, of which the following is a specification.

This invention relates to threshing machines and similar farm apparatus, and 10 more particularly to protecting covers therefor, and has for its object to provide a cover which may be attached especially to a threshing machine and which will include protecting curtains which may be quickly 15 and simultaneously lowered or raised as desired.

Another object is to provide a structure of 20 this character in which the curtain supporting portions may be raised or lowered as desired to suit different conditions and the curtain thus raised and lowered bodily.

Other objects and advantages will be apparent from the following description, and it will be understood that changes in the 25 specific structure shown and described may be made within the scope of the claim without departing from the spirit of the invention.

In the drawings forming a part of this 30 specification, and in which like numerals of reference indicate similar parts in the several views, Figure 1 is a side elevation of a threshing machine with the present invention applied thereto, Fig. 2 is a front view, 35 the front curtains being removed, Fig. 3 is a longitudinal section, Fig. 4 is a detail view showing the manner in which the actuating ropes and the curtains are attached to the supporting frame.

40 Referring now to the drawings, there is shown a threshing machine 5, upon which there are disposed a pair of uprights 6 and 7. These uprights are braced at their lower ends by diagonal members 8, and as shown, 45 they are formed of T-iron, the ribs 9 thereof being directed outwardly. A sleeve 10 is slidably engaged upon each of the uprights 6 and 7, these brackets 10 having forwardly extending webs 11, which are hollow and 50 which receive the ribs 9 of the uprights. The webs 11 are provided with horizontal passages 12 arranged for interchangeable registration with transverse passages 13 formed in the ribs 9, for the reception of retaining pins 14. In this way the sleeves 10 55 may be shifted vertically upon the uprights.

Similar sleeves 15 are engaged with the portions of the uprights above the sleeves 10, and geared upon these sleeves 15 there are a pair of parallel transversely extending end 60 frame members 17 and 18 respectively, which are connected at their ends by longitudinal frame members 19 and 20 respectively. The end frame members 17 and 18 are supported against rocking movement 65 upon the sleeves 15 by diagonal braces 21 connected with the end members at opposite sides of the sleeves 15 and extending downwardly and inwardly and having their lower ends seated in sockets 10' formed in the 70 sleeves 10. A supporting frame A is thus provided which may be adjusted vertically by movement of the sleeves 10 upon the uprights 6 and 7 as will be understood. Connecting devices 22 are located at the corners 75 of the frame A, and have sockets (not shown) which receive the ends of the members of the frame as shown. These members 22 also have sockets 23 which receive the outer ends of inwardly and upwardly inclined members 24 connected at their inner ends by means of a metallic device 25, which also receive and hold the end of a ridge pole 26. The side members 19 and 20 are beveled 80 to produce sharp outer edges D, and engaged 85 with these edges there are depending longitudinally extending side curtains 27, which coöperate with a canvas or other suitable cover 28 which is disposed upon the ridge 90 pole 26 and the members 24.

90 Disposed at their lower ends upon the end members 17 and 18, there are short uprights 28', which are secured at their upper ends to the ridge pole 26, and secured against the sides of these uprights there are boxings 95 29 in which there is revolvably mounted a longitudinally extending horizontal shaft 30. As shown, a central support 31 is provided for the frame A and is equipped with sleeves similar to the first named supports 6 and 7, one of these sleeves being connected to a transversely extending member 32 which is parallel to the members 17 and 18, and which is secured at its ends to the side members 19 and 20. A short upright 33 is mounted upon the member 32 and is secured to the ridge pole 26. The shaft 30 extends through a third boxing indicated at 29 upon the short upright 33, and mounted upon this 100 shaft at opposite sides of the upright 33 there is a drum, these drums being indicated at 34 and 35 respectively. A pair of drums 110

36 and 37 respectively are mounted upon the shaft 30 adjacent to the forward upright 28' and a similar pair of drums 38 and 39 are mounted upon the shaft 30 adjacent to 5 the rearward upright 28'. The curtains 27 are provided at their lower edges with attached rollers 40, and the curtains are rolled upwardly and inwardly around these rollers to be raised.

- 10 The curtains 27 and the covering fabric are secured to the side members 19 and 20 by means of transversely angular plates which extend longitudinally of the frame A as shown. These plates are shown at 41, and 15 are held in position by suitable fasteners 42. Each of these plates carries a plurality of outwardly extending eyes 43, one of these eyes being disposed opposite to each of the drums mounted upon the shaft 30. A cable 20 44 is engaged at its outer end with each of the eyes 43, and extends downwardly over the outer surface of the adjacent curtain, and inwardly beneath the rolled lower edge of the curtain and then upwardly and in- 25 wardly over a roller 45 mounted in the frame A, and thence to the corresponding drum of the shaft 30. The cables of each pair of drums extend oppositely therefrom, so that when the shaft is rotated in one direction all of the cables will be wound upon the drums and when the shaft is rotated in the opposite direction the cables will be un- 30 wound.
- 35 The shaft 30 extends beyond the forward short upright 28', as shown, and at this forward portion it carries a drum 46 about which there is engaged one turn of a continuous cable 47 which depends from the drum. It will thus be seen that when one

side of the cable 47 is pulled downwardly, 40 the drum 46 will be revolved and therewith the shaft 30 will be turned to rotate the drums 34, 35, 36, 37, 38 and 39, and wind their respective cables thereupon, thus raising the side curtains. When the cable 47 45 is moved oppositely, the cables will be unwound and the curtains will be allowed to drop. As shown the end uprights 6 and 7 are offset laterally from the central upright 31, to give room for the wind stacker of 50 the threshing machine. As shown, the ends of the cover are provided with eyelets Z for the attachment of supplemental curtains X.

What is claimed is:

The combination with a roof having a 55 series of spaced supports; of curtains secured to the lateral edges of the roof, rollers secured to the free edges of said curtains, said curtains being wound on said rollers as the curtains are raised, a single shaft extending longitudinally beneath said roof, a series of drums fixed on said shaft, means to rotate the shaft, and a plurality of series of curtain raising and rolling ropes, the ropes of each series each having one end secured 60 to a respective roof edge and extending around the respective curtain and roller, the remaining ends being all attached to said drums to wind thereon simultaneously 65 when the shaft is rotated in one direction 70 and thereby simultaneously roll up both curtains.

In testimony whereof I affix my signature, in presence of two witnesses.

ALLYN BOUGHTON.
